UNITED STATES PATENT OFFICE.

FRANK J. WILSON, OF NELSON, NEBRASKA.

WELDER'S TABLE AND CLAMP.

Application filed May 5, 1927. Serial No. 188,162.

This invention relates to devices for holding two parts in set position while they are being welded either by the acetylene process or while they are being electrically welded or otherwise treated.

The general object of the invention is to provide a table and clamps adjustable upon the table to any desired position having adjustable jaws whereby the two parts of the article to be welded are held rigidly in position against any chance of relative movement.

A further object is to provide a table so constructed that the clamps may be disposed in any desired position thereon and provide clamps which are mounted upon brackets which in turn engage the table for swinging movement in a horizontal plane.

A further object is to provide brackets which will permit the clamps to be adjusted up or down and provide means for holding the clamps rigidly in their adjusted positions.

Another object is to provide a table of this character having means whereby a plurality of clamps may be disposed in a large variety of differently related positions so that the object to be welded, soldered, or otherwise worked upon shall be rigidly held.

My invention is illustrated in the accompanying drawings, wherein:—

Figure 1 is a top plan view of the device;

Figure 2 is a bottom plan view of the table;

Figure 3 is an elevation of one of the clamps;

Figure 4 is a section on the line 4—4 of Fig. 3;

Figure 5 is a section on the line 5—5 of Fig. 3;

Figure 6 is a section on the line 6—6 of Fig. 3;

Referring to these drawings, 10 designates the table which may be made of sheet metal and be supported upon legs or in any suitable manner. This table is preferably formed with a reinforced rim 11 and transverse braces 12, the rim and braces being formed with a plurality of holes 13. The braces extend across the under face of the table and may be riveted thereto, and the upper face of the table is flat throughout its entire extent.

Coacting with the perforations 13 are the supporting brackets 14. These are formed of strips of metal angularly bent at one end

as at 15 and reduced in width, so that this end may pass through a perforation and the bracket is formed with a longitudinal slot 16. The reduced somewhat hook shaped extremity 15 is adapted to be inserted into any one of the perforations 13 and to be rotatably adjusted in said perforations. The hook shaped extremity permits the bracket to be shifted in any direction into angular relation to the table but the weight of the clamping devices to be hereafter described will normally hold this bracket in a position at right angles to the face of the table. Passing through the slot 16 of each bracket is a screw-threaded clamping rod 17 formed with a jaw 18 at one end, the inner face of this jaw being toothed. Coacting with the jaw 18 is a sliding jaw 19 having that face confronting the jaw 18 toothed and jaw 19 is held in its adjusted position by a nut 20 having a handle. A washer may be disposed between the nut 20 and the jaw 19. Also mounted upon the screw-threaded rod 17 are the two clamping nuts 21, each having handles disposed one on each side of the supporting bracket 14. When these nuts are turned up on the rod 17 they will clamp the supporting bracket firmly between them and as a consequence hold the supporting rod 17 in a vertically adjusted position upon the supporting bracket. When the nut 20 is turned up it will force the jaw 19 against the object held between the jaws 18 and 19. Thus these jaws may be clamped securely upon the object to be supported.

The primary object of this invention is to provide means whereby the sections of a part to be welded or otherwise joined may be held in proper abutting position with the broken surfaces or the surfaces to be welded in contact with each other. I have illustrated in Figure 1 the manner in which these clamping and supporting devices will be used to hold an article A in position with the broken edges a in contact. This is purely illustrative of the use of my device and any number of the clamping sets as I term them may be used, it being understood that each clamping set includes the supporting bracket 14, the rod 17, the clamping nuts 21, the clamping jaws 18 and 19 and the clamping nut 20. These clamping sets may be disposed in any desired position upon the table and when clamped in position will hold the article to be welded firmly in place against any accidental shifted movement so

that the workman can weld, solder, or otherwise act upon these parts. The clamping sets are particularly adapted for use in clamping articles having a more or less irregular formation which would be extremely difficult to clamp or hold in an abutting position by any other means than that disclosed. It will be understood that as many clamping sets may be used as is necessary to hold the work properly and that a very large number of different adjustments may be made. I do not wish to be limited to the exact construction of the sets nor to the number of sets used as obviously these will depend upon the work. Ordinarily three sets are sufficient, two sets to hold the two portions of the work, the third set to hold the two portions of the work in tight engagement with the work as illustrated in Figure 1.

The rod 17 is more or less rectangular in cross section so that the collars at the ends of the jaws may have sliding engagement on the rod in rotative engagement therewith.

25 The rod is rotatively adjustable in the slot 16.

I claim:—

30 1. A welder's table having a plurality of perforations through it, supporting brackets, each having an end adapted to be engaged with the table through one of said perforations, each bracket being longitudinally slotted, a screw-threaded rod passing through the slot of each bracket, clamping nuts engaging the rod and adapted to engage in each side of the bracket to hold the rod in adjusted position, clamping jaws carried by the rod, the jaws being relatively

shiftable toward or from each other, and means for holding the clamping jaws in adjusted position.

5 2. A welder's table having a plurality of perforations through it, and work holding means comprising a bracket having one end formed to engage with any one of said perforations, the bracket being vertically slotted, a screw-threaded rod passing through the slot of the bracket, clamping bolts on the rod in vertically adjusted position, the rod being formed at one end with a jaw, a 45 jaw slidably mounted upon the rod toward and from the fixed jaw, and a nut operatively engaging the last named jaw to hold the jaw in adjusted position.

15 3. A welder's table having a plurality of perforations, a work supporting device including a bracket longitudinally slotted, and having one end reduced to pass through a perforation and angularly bent, a screw-threaded rod passing through the slot of the 50 bracket, nuts on opposite sides of the bracket and clamping jaws carried on the rod, one of said jaws being adjustable toward or from the other jaw.

20 4. A welder's table having a plurality of perforations, a work supporting device including brackets each having one end reduced to pass through a perforation and angularly bent, clamping rods vertically and longitudinally adjustable upon the brackets, 55 and clamping jaws carried by said rods and relatively adjustable toward or from each other.

25 In testimony whereof I hereunto affix my signature.

FRANK J. WILSON.
